UNITED STATES PATENT OFFICE

GEORGE H. PERKINS, OF WELLESLEY, MASSACHUSETTS, ASSIGNOR TO POWDRELL & ALEXANDER, INC., OF BOSTON, MASSACHUSETTS, A CORPORATION OF MASSACHUSETTS

DESIGN FOR A TEXTILE FABRIC

Application filed May 15, 1929. Serial No. 31,237. Term of patent 3½ years.

To all whom it may concern:

Be it known that I, GEORGE H. PERKINS, a citizen of the United States of America, residing in Wellesley, in the county of Norfolk and Commonwealth of Massachusetts, have invented a new, original, and ornamental Design for Textile Fabric, of which the following is a specification, reference being had to the accompanying drawing, forming part thereof.

The figure is a face view of the fabric.

The arrangement is carried forward throughout the surface of the design in accordance with the representative illustration.

The motifs are of contrasting color with the fabric upon which they are superposed.

I claim:

The ornamental design for a textile fabric as shown and described.

Signed by me at Boston, in the county of Suffolk and Commonwealth of Massachusetts, this 10th day of May, 1929.

GEORGE H. PERKINS.
